UNITED STATES PATENT OFFICE

92,623

DESIGN FOR A HOUSING FOR DRIERS AND SIMILAR MACHINES

James A. Noonan, Lowell, Mass., assignor to C.
G. Sargent's Sons Corporation, Graniteville,
Mass., a corporation of Massachusetts

Application December 2, 1933, Serial No. 49,925

Term of patent 14 years

To all whom it may concern:

Be it known that I, JAMES A. NOONAN, a citizen of the United States, residing at Lowell, in the county of Middlesex, and State of Massachusetts, have invented a new, original, and ornamental Design for a Housing for Driers and Similar Machines, of which the following is a specification, reference being had to the accompanying drawing, forming part thereof.

The figure is a view in perspective of a housing for driers and similar machines embodying my design, the opposite side and end of the design being substantially of the same appearance as the side and end shown.

I claim:—

The ornamental design for a housing for driers and similar machines, as shown and described.

JAMES A. NOONAN.
